ANGLE OR JOINT BAR FOR INSULATED RAILWAY RAIL JOINTS

Filed June 22, 1929

By *Watson E. Coleman*
Attorney

UNITED STATES PATENT OFFICE

HANS J. HAUSKEN, OF MYERS, MONTANA

ANGLE OR JOINT BAR FOR INSULATED RAILWAY RAIL JOINTS

Application filed June 22, 1929. Serial No. 372,921.

This invention relates to railway rail joints of the insulated type, and more particularly to the angle bars of such joints.

The invention has for one of its objects to improve angle or joint bars of this character to the end that their tendency to surface cut the ties; their tendency to slide freely with respect to the ties, and their tendency to permit the ties to become laterally displaced, will be overcome.

The invention has for a further object to provide angle or joint bars of the character stated which shall be adapted to be firmly secured to the ties without the aid of tie plates and which, while holding the ties against lateral displacement, will permit them to have a limited lateral movement with respect thereto.

To attain the foregoing and other objects, the nature of which will appear as the description proceeds, the invention comprehends the provision of angle or joint bars of the character stated which shall embody base flanges of increased width and having their outer or remote edges corrugated or waved transversely to provide tie receiving recesses.

The invention is hereinafter more fully described and claimed, and illustrated in the accompanying drawings, wherein:—

Figure 1 is a top plan view of an insulated railway rail joint embodying angle or joint bars constructed in accordance with my invention;

Figure 2 is a view in side elevation of the joint; and

Figure 3 is a sectional view taken on the vertical plane indicated by the line 3—3 of Figure 2.

Referring in detail to the drawing, A and B designate the meeting ends of a pair of railway rails. C and D designate the angle bars of an insulated joint for the rails A and B. E designates the bolts by which the angle or joint bars C and D are secured in applied position, and F designates the insulation of the joint.

The angle or joint bars C and D are similar, and each comprises a base flange 1, a foot flange 2 and a web flange 3. In accordance with my invention, the base flanges 1

are greater in width than the corresponding parts of the angle or joint bars now in use. The base flanges 1 extend for a considerable distance laterally beyond the bases of the rails A and B, and they gradually decrease in thickness in the direction of their outer longitudinal edges. The outer portions of the base flanges 1 are corrugated or waved transversely to provide recesses 4 for the reception of the ties G that are arranged at opposite sides of the meeting ends of the rails A and B. The tie receiving recesses 4 are provided with flat upper surfaces or tie seats 5 which are arranged in the plan of the lower surfaces of the inner portions of the base flanges 1.

Two ties are used to support an insulated joint, and these ties are arranged at opposite sides of the meeting ends of the rails.

In order to insure the proper supporting of the joint so as to prevent displacement of the insulation or destructive strain thereon, it is necessary that the ties be maintained in proper spaced relation to the meeting ends of the rails. Angle or joint bars of the construction now in use will not maintain the ties in proper place, and furthermore, they have a tendency to surface cut and slide freely with respect to the ties.

My angle or joint bars overcome these objections. The increased width of their lower or tie contracting surfaces prevents them from surface cutting the ties, and also prevents them from having any tilting movement on the ties. The seats 5 rest upon the ties. The downwardly extending portions at opposite sides of the seats, while permitting limited lateral movement of the ties, hold them against displacement with respect to the meeting ends of the rails. The limited movement permitted the ties results from the fact that the upper or tie engaging surfaces of the recesses are slightly wider than the ties. Furthermore, the waving or corrugating of the outer portions of the base flanges 1 of the angle or joint bars, to provide the tie receiving recesses, materially strengthens and reinforces the bars. The inner portions of the base flanges 1 are uninterrupted and straight throughout their entire length so as

to provide a highly efficient support for the rails and insulation, particularly at the meeting ends of the rails.

While I have described the principle of the invention together with the structure which I now consider the preferred embodiment thereof, it is to be understood that the structure shown is merely illustrative and that such changes may be made, when desired, as fall within the scope of the invention as claimed.

I claim:

Angle or joint bars for an insulated rail-way rail joint provided with base flanges having inner and outer portions, said inner portions being adapted to underlie rail bases and being uninterrupted and straight throughout their entire length, said outer portions being adapted to be located wholly and laterally beyond the rail bases and transversely corrugated to provide tie seats at opposite sides of the longitudinal centers of the bars and to provide downwardly extending tie retaining portions between and laterally beyond the seats, said seats being wider than the usual ties, and said seats being alined with the lower surfaces of said inner portions.

In testimony whereof I hereunto affix my signature.

HANS J. HAUSKEN.
